UNITED STATES PATENT OFFICE.

HENRY J. HAUSER, OF ROCHESTER, NEW YORK.

WINDOW-SCREEN.

No. 844,867.

Specification of Letters Patent.

Patented Feb. 19, 1907.

Application filed October 4, 1906. Serial No. 337,448.

To all whom it may concern:

Be it known that I, HENRY J. HAUSER, a citizen of the United States, residing at Rochester, in the county of Monroe and State of New York, have invented certain new and useful Improvements in Window-Screens; and I do hereby declare the following to be a full, clear, and exact description of the invention, such as will enable others skilled in the art to which it appertains to make and use the same.

My invention relates to an improvement in window-screens; and the object of my invention is to produce a screen which will be unrolled as the window is opened and to provide means whereby insects are prevented from entering a house when the window is open, either above or below the screens or between the parts of the window.

A further object is to provide a screen which may be adjusted to any size of window and which will automatically adjust itself to the varying conditions of strain as the window is raised or lowered, the screens for this reason being made of two separate overlapping parts, said parts being mounted on a single roller.

With the objects stated in view my invention consists in the construction and combinations of parts, as hereinafter described and claimed.

In the accompanying drawings, Figure 1 is a front view of a window equipped with my device. Fig. 2 is a vertical section thereof. Fig. 3 is a side view of one of the rollers, partly broken away, on which said screen is mounted. Fig. 4 is a bottom view of the same roller. Fig. 5 is a section of said roller on the line 5 5 of Fig. 4. Fig. 6 is a section of the same roller on the line 6 6 of Fig. 4. Fig. 7 is a bottom plan view of the device for closing the space between the two sashes of the window. Fig. 8 is a front view of the shutter for closing the space around the screen as the latter is unrolled. Fig. 9 is a cross-section on the line 9 9 of Fig. 7. Fig. 10 is a cross-section on the line 10 10 of Fig. 8, and Fig. 11 is a perspective view of one of the spring-clips for holding one of the halves of the screen.

a represents a window-frame, *b* the lower sash, and *c* the upper sash, thereof. To the upper part of the inside of the lower sash are fastened the spring-clips *d*, consisting of a flat metal plate provided with openings *e* for the passage of nails or screws and a

tongue cut from said plate and bent downwardly and provided with an aperture *f*. Each screen *g* is made of two parts, as shown in Fig. 1, both parts being wound on a single roller *h*. The screens are made of artistic construction and with finished edges. They may be ornamented, if desired.

The top of each screen is provided with a plate *i*, to which the screen is fastened upon its entire upper edge, and this plate is provided with a central projecting pin *j*, which is adapted to pass behind the spring-clip and be inserted in the aperture *f*. The upper sash is similarly provided with a similarly-arranged screen, except that it unrolls downward instead of upward.

By the construction mentioned, as the sash *b* is raised the two parts of the screen automatically adjust themselves to varying conditions of tension, always keeping a perfectly smooth even surface in contact with the window-frame. The screen of course might be built into the lower part of the window-frame; but the simpler construction is to have the roller mounted on pins *k*, screwed or nailed to the window-frame, thus affording a ready means whereby the screens may be put up in houses already built. As the screen unrolls, however, a space would be left underneath the screen, through which insects might enter the house, and to prevent this I provide in front of each screen and extending the width of the window a pivoted shutter *l*, which is pressed by the spring *m* into contact with the screen mounted on the roller.

The roller, as shown in Figs. 3 and 4, is adjustable, so that it may be fitted upon windows of different sizes. It is made in two parts, portions being cut away at right angles on the ends of the two different parts, as shown in Figs. 3 and 4. These portions are similar in shape, but oppositely arranged. One of them is provided with a groove *n* and the other with a tongue *o* fitting therein. The parts are held in their adjusted position by means of a screw *p*, fastened in one of the movable portions of the roller, the other portion being provided with a countersunk slot *q*, the screw *p* being adapted to fit against the ledges in the bottom of said slot when it is screwed home. The roller is hollow for a portion of its length and provided on the inside with a spring *r*, which continually tends to roll the two parts of the screen upon the roller. In the bottom of the roller is cut a

long slot *s* with an enlarged portion *t*, and the other end of the slot terminates in a countersunk portion *u*. In assembling the parts the end of the spring *r* is put through the opening *t* and then slipped along the slot *s* and the bent end thereof dropped into the countersunk portion *u*, thereby leaving the outside of the roller smooth and securely holding the spring. The roller is also provided with a slot *v*, extending across its whole length and running into the roller at an angle thereto. The end of the screen is placed in this slot, and then said ends are secured in position, by a metal clip *w*, extending the whole length of the roller. In order that the shutter *l* may be fitted to windows of any size, it also is made in two overlapping parts, these parts being held together by means of a hinge-plate *x*, which runs in a slot *y* of the parts of the shutter. When a window is open, flies or other insects often get in between the sashes, even if the openings below and above the sashes are closed. I have provided special means to prevent this. (Shown in Figs. 2 and 7.) To the bottom of the upper sash *c* is secured a two-part shutter-holder *z* by means of hinged clips 1. The shutter-holder *z* is made in two parts, so that it may be fitted to windows of any size, and the hinges 1 run in slots in the parts of the shutter-holder *z*. This shutter-holder is made, preferably, of spring metal, and the front part of it is bent down. At intervals parts 3 are struck up from the projecting portion of the shutter-holder *z*, and pieces of stiff paper 4 are inserted above the clips, which are then bent up. Any desired material may of course be used instead of paper. In Fig. 2 this device is shown completely closing the space between the lower window-pane and the lower edge of the upper sash. It is obvious that if it were attempted to push one sash past the other this shutter would catch and become broken unless special means were used to prevent it. These means consist of the inclined plates 5, attached to the back of one of the window-sashes, and the shutter is provided with curved projecting portions 6, which strike the inclined portions, throwing the shutter backward out of contact with the sash. A spring 7 normally keeps the shutter in contact with the window-pane, and this spring yields when the parts 6 strike the parts 5; but as soon as the pressure is removed the parts immediately revert to their original position, as shown in Figs. 2 and 9.

Having thus described my invention, what I claim as new, and desire to secure by Letters Patent, is—

1. The combination with a window-sash, of a two-part screen mounted on a spring-controlled roller, each part of said screen being provided with a plate having a central

pin, and spring-plates fastened to the sash engaging said pin, said first-named plates being free to move around said pins as centers substantially as described.

2. The combination of a window-sash, spring-plates each having an aperture near its end, fastened to said sash, a spring-controlled roller, a two-part screen wound upon said roller, the parts of said screen overlapping each other at their meeting edges, each part of said screen having a plate along one edge thereof, and each plate being provided with a centrally-located pin, said pins being adapted to be pivotally supported in the apertures of the corresponding spring-plates, and means for closing the space underneath said screens as they are unrolled by the opening of the window, substantially as described.

3. The combination of a spring-controlled roller made in two parts, said parts being adjustable, one upon the other, for different-sized windows, a two-part screen wound upon said roller, the parts of said screen overlapping each other, a plate along the outer edge of each one of said screens and having a central pin projecting outwardly, and spring-plates fastened to the window-sash, each having an aperture in its outer end adapted to fit over one of the pins in said plate, substantially as described.

4. The combination of a spring-roller provided with an inclined slot thereon, a two-part screen, one end of which is adapted to be placed in said inclined slot, means for fastening the screen in said slot, a plate secured on the outer end of each part of the screen, each of said plates having a centrally-located pivot-pin, and spring-plates secured to the window-sash each having an aperture near one end thereof, with which one of said pivot-pins is adapted to engage, said first-named plates being free to turn on said pins, substantially as described.

5. A roller for window-screens consisting of two parts, one provided with a tongue, and the other with a corresponding groove, so that the parts may be adjusted upon each other, one of said parts being also provided with a countersunk slot, a screw passing through said slot and adapted to hold said parts together, an inclined groove running the whole length of said roller for the reception of one end of the screen, said roller being hollow for a portion of its length, a spring in said hollow portion, and a slot through said roller having an enlargement at one end and a countersunk portion at the other, substantially as described.

6. The combination of a spring-roller made in two parts, adjustable upon each other, a two-part screen secured to said roller the parts of said screen overlapping each other, a plate secured to one end of each part of said screen, each plate being provided with

5 a central pivot-pin, spring-plates fastened to the window-sash, each provided with an aperture near its outer end adapted to engage the pivot-pins on said plates, said first-named plates being free to turn on said pins and a spring-controlled two-part shutter adapted to close the space left by said screen as it unrolls, substantially as described.

10 7. The combination of a window-sash, shutter-supporting means pivoted to the bottom of said sash, a spring supported on said sash, and normally pressing said shutter forward, said shutter being provided with curved extending portions, and inclines 15 mounted upon the other sash, so that said sashes may be slipped past each other without catching said shutter, substantially as described.

8. The combination of a window-sash,

hinges fastened thereto, a two-part shutter-holder supported by said hinges, the parts overlapping each other, a shutter carried by said shutter-holder and provided with curved extensions near its ends, a spring supported on said sash and normally forcing said shutter and shutter-holder forward, and inclines located on the other window-sash with which the extensions on said shutter-holder are adapted to engage, whereby the sashes may be slipped past each other without catching 25 the shutter or shutter-holder, substantially as described.

In testimony whereof I affix my signature in presence of two witnesses.
